ATTORNEYS

UNITED STATES PATENT OFFICE.

RALPH F. SCHNEIDER, OF JERSEY CITY, NEW JERSEY.

BLEEDING APPARATUS.

Application filed October 21, 1921. Serial No. 511,718.

To all whom it may concern:

Be it known that I, RALPH F. SCHNEIDER, a citizen of the United States, and a resident of Jersey City, in the county of Hudson and State of New Jersey, have invented a new and Improved Bleeding Apparatus, of which the following is a full, clear, and exact description.

This invention relates to improvements in bleeding apparatus which is commonly used for extracting blood from the body for the purpose of making blood tests.

The common practice heretofore has been to use a vacuum tube with a relatively long neck and a hypodermic needle. The neck of the tube and the needle have been coupled by a short length of rubber hose. After the needle has been inserted in a blood vessel it has been customary to use a pair of pincers or other suitable tool to squeeze the rubber tubing and break the neck of the vacuum tube, thus creating a suction to draw blood through the needle into the tube.

With the old form of apparatus it has practically been impossible to manually break the neck of the vacuum tube after the insertion of the needle since no adequate means has been provided for holding the needle steady while such breaking was done.

An object of this invention is to provide an improved form of support and coupling, which is interposed between the needle and tube, and which makes it possible for the neck of the tube to be manually broken while the needle is in the flesh.

A further object is to provide an improved apparatus using a coupling of this character, which will expedite the bleeding of a patient, and which will be simple and practical in construction, durable and efficient in use, capable of sterilization, and with which there is absolutely no danger of injuring the patient because of the lack of a firm support for the needle.

With these and other objects in view, the invention consists in certain novel features of construction and combinations and arrangements of parts as will be more fully hereinafter described and pointed out in the claims.

In the accompanying drawings:

Figure 1 is a perspective view illustrating the manner of use of my improved apparatus;

Figure 2 is a view in elevation of the ap-

paratus with parts broken away for clearness; and

Figure 3 is an enlarged view in section through the neck of the vacuum tube.

Referring in detail to the drawings, 1 represents a hypodermic needle, formed at one end with a socket member such as 2. A glass vacuum tube 3 is formed with a relatively long tapered neck 4, which may be easily broken. My improved coupling for the tube and needle comprises a stem 5 having a short longitudinal bore 6 at one end which communicates with a nipple 7 located at an angle to the longitudinal and transverse planes of the stem. A thumb-receiving handle or disc 8 is secured to the other end of the stem 5 and a laterally projecting finger receiving pin 9 is fixed to the stem adjacent the nipple 7 and on the opposite side of the stem from the nipple.

The socket portion 2 of the hypodermic needle 1 receives the bored end of the stem 5 and frictionally fits the same. A short length of rubber tubing 10 is connected to the outer end of the nipple 7 and receives the neck 4 of the vacuum tube or bleeding tube 3. It will be noted that the tube 10 is of such a length that the extremity of the neck 4 of the tube is located within the nipple 7.

The manner of use of the device is illustrated clearly in Figure 1, where it will be seen that the operator places his thumb against the disc 8 and his middle finger engages the pin 9 to firmly hold the same after the needle and bleeding tube have been attached. After the needle has been inserted into a patient, the operator uses the index finger to exert pressure on the neck 4 of the tube 3. Inasmuch as the extremity of this neck extends into the nipple 7, it will be seen that a very slight pressure of the neck will cause breaking of the tube so that the vacuum in the tube 3 will suck blood through the needle 1, bore 6, nipple 7 and tubing 10 and into the bleeding tube 3. It will be seen that the needle may be firmly held within the flesh while the neck of the vacuum tube is broken so that there is absolutely no danger of tearing a patient's flesh during the operation.

Although I have illustrated one of the preferred embodiments of my invention, it will be evident that various slight changes and alterations might be made in the gen-

eral form and arrangement of the parts described without departing from the invention; and hence I do not wish to limit myself to the precise details set forth, but shall consider myself at liberty to make such slight changes and alterations as fairly fall within the spirit and scope of the appended claims.

I claim:

1. An apparatus of the class described, including a handle having a passage therein adapted to communicate with a hypodermic needle, a rigid nipple fixed to the handle and communicating with the passage, and a flexible airtight coupling member adapted to hold the reduced breakable end of a vacuum tube within said nipple.

2. In an apparatus of the character described, a rigid tubular member, a vacuum tube including a reduced breakable end, and

a flexible airtight coupling member adapted to hold said end of the vacuum tube within the rigid tubular member.

3. An apparatus of the character described, including a handle, thumb and finger receiving elements carried by the handle, said handle having a passage in one end adapted to communicate with a hypodermic needle, a rigid nipple extending at an angle to the handle, and communicating with the passage, a flexible airtight coupling member adapted to maintain the breakable end of a vacuum tube within the nipple, and said thumb and finger receiving elements being so arranged that one finger of a hand holding the handle is left free to break the end of the tube by exerting pressure on said flexible coupling member.

RALPH F. SCHNEIDER.
